UNITED STATES PATENT OFFICE.

FRANK NOVOTNY, OF BADGER, MINNESOTA.

NECK-YOKE.

SPECIFICATION forming part of Letters Patent No. 626,923, dated June 13, 1899.

Application filed January 17, 1899. Serial No. 702,394. (No model.)

To all whom it may concern:

Be it known that I, FRANK NOVOTNY, a citizen of the United States, residing at Badger, in the county of Roseau and State of Minnesota, have invented certain new and useful Improvements in Neck-Yokes; and I do hereby declare the following to be a full, clear, and exact description of the invention, such as will enable others skilled in the art to which it appertains to make and use the same.

My invention has for its object to provide an improved neck-yoke; and to this end it consists of the novel devices and combinations of devices hereinafter described, and defined in the claims.

The invention in its preferred form is illustrated in the accompanying drawings, wherein like characters indicate like parts throughout the several views.

Figure 1 is a view in front elevation, showing my improved neck-yoke in working position on the end of a wagon or carriage pole. Fig. 2 is a plan view of the neck-yoke. Fig. 3 is a vertical section taken approximately on the line $x^3 x^3$ of Fig. 1; and Fig. 4 is a view taken in horizontal section through the central portion of the neck-yoke, some parts being shown in full.

The body of the neck-yoke is made up of an endless metallic strap 1 and a channel-shaped spacing or intermediate plate 2. The endless marginal strap 1 is bent to form a truss-like body with looped ends 3—that is, the body formed by the endless strap 1 is spread apart at its central portion considerably farther than it is at its end portions and its end portions are turned upward to form seats for the end rings 4. The intermediate or spacing plate 2 fits the space between the sides formed by the strap 1, but terminates short of the looped ends thereof. The flanges of the spacing-plate 2 are preferably somewhat less in width than the marginal strap 1, and they are rigidly secured thereto at their ends and inward of their ends by rivets 5. The central portion of the lower flange of the spacing-plate 2 is provided with a segmental plate-like projection 6 for a purpose which will presently appear. A pair of eyebolts 7 are passed through the sides of the strap 1 and through the flanges of the spacing-plate 2 close to the central portion of the neck-

yoke, and, as shown and preferred, the upper ends of these eyebolts are riveted to secure the parts together. To render the construction rigid and prevent the inward springing of the flanges of the spacing-plate 2, short pipe-sections or spacing-tubes 8 are placed between the said flanges, and the stems of the eyebolts 7 are passed therethrough while being placed in working positions. The pole-ring 9 is passed through and held by the eyes of the eyebolts 7.

10 indicates the outer end of a wagon or carriage pole, which, as shown, is provided with 65 a pole-tip casting 11, having an ordinary depending lug or stop 12.

Fig. 3 serves to best illustrate the position of the neck-yoke when applied in working position to the wagon-pole and to the harness 70 of the draft-animals. By reference to said Fig. 3 it will be seen that the segmental plate or projection 6 is bent downward, so that it overlies and preferably projects slightly beyond the end of the pole or pole-tip casting 75 11. The form of the said segmental plate 6 is such that it will always cover the outer end of the said pole regardless of the swinging movements of the neck-yoke, and on account of the function which this plate 6 performs I 80 term the same the "pole-tip guard or shield."

It is a well-known fact that great annoyance and often serious accidents are caused by the reins or lines being caught under the end of the pole. It is the primary object of 85 my present invention to render it impossible for the reins or lines to become thus engaged with the end of the pole, thus removing the above cause of annoyance and rendering accidents from the above-noted source impossible. It is evident from the foregoing description that the so-called "pole-tip guard or 90 shield" accomplishes the above-desired objects. However, the general construction of the neck-yoke regardless of this pole-tip guard 95 or shield is thought to involve novel features of improvement and that a very simple, efficient, and cheap construction is thereby provided.

It will also be understood that my invention above described is capable of considerable modification as to details of construction.

What I claim, and desire to secure by Letters Patent of the United States, is as follows:

1. In a neck-yoke, the combination with a marginal metallic strap formed from a single piece or strip and forming the outline of the neck-yoke, of the spacing-plate secured between the sides of said marginal strap and extending approximately from end to end of the neck-yoke, substantially as described.
2. In a neck-yoke, the combination with the marginal metallic strap forming the outline of the neck-yoke, of the spacing-plate secured between the sides of said marginal strap 1, and provided with the centrally located and projecting guard-plate adapted to overlie the end of the pole, substantially as described.
3. In a neck-yoke, the combination with the endless marginal strap 1, formed with the end loops 3, of the spacing-plate 2 secured between the sides of said strap 1 but terminating short of the ends thereof and provided with

the segmental guard-plate or projection adapted to overlie the end of the pole, substantially as described.

4. In a neck-yoke, the combination with the endless marginal strap 1, of the flanged spacing-plate 2, rigidly secured between the sides thereof and provided with the segmental guard-plate or projection 6, the eyebolts 7, passed through the sides of said strap and the flanges of said spacing-plate, the spacing-tubes or pipe-sections 8 on the stems of side eyebolts, and the pole-ring 9 secured by said eyebolts, substantially as described.

In testimony whereof I affix my signature in presence of two witnesses.

FRANK NOVOTNY.
